C. Harpman
Attorney

UNITED STATES PATENT OFFICE.

SERENA SOLOMON, OF YOUNGSTOWN, OHIO.

CURTAIN-STRETCHER.

1,342,396.

Specification of Letters Patent.

Patented June 1, 1920.

Application filed February 21, 1920. Serial No. 360,544.

To all whom it may concern:

Be it known that I, SERENA SOLOMON, a citizen of the United States of America, residing at Youngstown, in the county of Mahoning and State of Ohio, have invented certain new and useful Improvements in Curtain-Stretchers, of which the following is a specification.

This invention relates to curtain stretchers, and has for its object the providing of a stretcher economical of manufacture, collapsible, adjustable, and mounted upon a support stand in a horizontal position.

Another object of the invention is to provide two inner side members, adjustably supported, provided with pins upon both the inner and outer edges of same.

Another object of the invention is to provide an L-iron as a supporting and fastening means for the inner ends of an end member of the frame.

A still further object is to provide a locking means for the other end member of the frame.

With these and other objects in view, this invention consists of certain novel combinations, constructions, and arrangements of parts, as will be hereinafter fully described and claimed.

30 In the accompanying drawings, Figure 1 is a perspective view of the invention.

Fig. 2 is a detail view showing means of locking inner ends of an end member of the frame.

35 Fig. 3 is a detail view showing means of securing the inner ends of the other end member of the frame.

Referring to the accompanying drawings by numerals, it will be seen that the base 40 of the support stand consists of a base support 1, upon this base support 1 is securely attached support stand legs 2 and 3. By referring to Fig. 1, it will be seen that these support stand legs are pivoted near their 45 central portion by means of bolts 4. Upon the upper ends of said support stand legs 2, are secured by means of hinges 5, the ends of the sides 6; to the support stand legs 3 is pivoted by any suitable means an end 50 member 7 of a rectangular frame. Upon the top of the ends of said end member 7 rests the other ends of the sides 6, secured thereon by means of bolts 8.

The end member 9 of the rectangular frame is supported underneath the sides 6 by means of the adjusting bolts 10. By re-

ferring to Fig. 1 it will be seen that the adjusting bolts project through slots 11 in the sides 6 of the rectangular frame, and that the end 9 is held in slidable relation to the sides 6. It will be seen that the sides 6 and the ends 7 and 9 are provided with pins 12. A pair of inner side members 13 are adjustably secured to the end members 7 and 9 by means of slots 14 and 15 therein and the adjusting bolts 16. It will be seen that the inner side members 13 are provided with pins 17 upon their inner and outer edges and that the adjusting bolts 16 pass through the slots 18 of the inner side members 13.

When it is desired to fold the device the locking arm 19 is pulled outwardly beyond the end of securing arm 20, thereby releasing the contact of the locking arm 19 with a securing arm 21. When the key arm 22 is released from the staple 23, the inner end 26 of the end member 9 may be slipped inwardly from the support 24 of the L-iron 25, thereby withdrawing the staple from the slot 27. The end member 7 may now be folded downwardly upon the hinge 28, thereby allowing the base supports 1 to approach each other and the side members 6 and 6 to fold against each other.

What I claim is:

1. In a device of the class described, a folding support stand, a rectangular frame hinged to the upper ends of said support frame, side members of said frame provided with pins upon their inner edge, slots within said side members, one end of said members resting upon an end member of frame, the other hinged to upper ends of support stand, an end member provided with pins upon its inner edge, said end member formed in two equal lengths, an L-iron secured to one end of said member, said L-iron carrying a key member, a slot in end of said L-iron, a staple secured in end of the other end member so as to project through said slot when the two end members are placed end to end, said end members adjustably supported underneath above mentioned side members of frame, an end frame member hinged to upper ends of support stand, said end member provided with pins upon its inner edge, hinged at its central portion, said hinge secured upon the upper surface of said end members—a locking means for holding said end member in horizontal position, two adjustable

inner side members, the same projecting through slots in above mentioned end members, provided with pins upon both outer and inner edges, substantially as described 5 for the purpose set forth.

2. In a device of the class described, having in combination with a folding support stand, a rectangular frame hinged to the upper ends of said support frame, side 10 members of said frame provided with pins upon their inner edge, slots within said side members, one end of said members resting upon an end member of frame, the other hinged to upper ends of support stand, an 15 end member provided with pins upon its inner edge, said end member formed in two equal lengths, an L-iron secured to one end of said members, said L-iron carrying a key member, a slot in end of said L-iron, a 20 staple secured in end of the other end member so as to project through said slot when the two end members are placed end to end, said end members adjustably supported underneath above mentioned side members of

frame, and end frame member hinged to 25 upper ends of support stand, said end member provided with pins upon its inner edge, hinged at its central portion, said hinge secured upon the upper surface of said end members,—a locking means for 30 holding said end member in horizontal position, two adjustable inner side members, the same projecting through slots in above mentioned end members, provided with pins upon both outer and inner edges, substantially 35 as described for the purpose set forth.

3. In a device of the class described, one end of a rectangular frame hinged at its central portion, a locking bar secured to outer edge of said end member, a securing 40 arm above said locking bar, a securing arm underneath said locking arm, substantially as described for the purpose set forth.

In testimony whereof I affix my signature.
SERENA SOLOMON.
